Primary Examiner — Carol Rademaker*Assistant Examiner* — Dana L Sipos(74) Attorney, Agent, or Firm — Nixon Peabody, LLP; Jeffrey L. Costellia(57) CLAIM

We claim the ornamental design for a bottle, as shown and described.

DESCRIPTION

FIG. 1 is a top, rear, right side perspective view of a bottle showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings showing a portion of the bottom surface of the bottle illustrate the portions of the design that form no part of the claim.
